UNITED STATES PATENT OFFICE.

JOSEPH C. SCHNEBLE, OF DAYTON, OHIO, ASSIGNOR OF ONE-HALF TO THEODORE C. SCHNEBLE, OF DAYTON, OHIO.

CARBURETER FOR INTERNAL-COMBUSTION ENGINES.

No. 889,487.

Specification of Letters Patent.

Patented June 2, 1908.

Application filed May 28, 1907. Serial No. 376,100.

To all whom it may concern:

Be it known that I, JOSEPH C. SCHNEBLE, a citizen of the United States, residing at Dayton, in the county of Montgomery and State of Ohio, have invented a certain new and useful Improvement in Carbureters for Internal-Combustion Engines, of which the following is a specification.

The object I have in view is to produce a carbureter for internal combustion engines which will be simple in construction and efficient in operation, will produce an effective vaporization of the gasolene or other liquid fuel employed when the engine is starting up and running slowly, will provide an ample air supply under all conditions of operation, will secure an effective mixture of the fuel and air and will enable the ready adjustment of the relative supplies of fuel and air so as to produce the proper mixture most effective for different kinds or grades of the liquid fuel; all as more fully hereinafter explained and pointed out in the claims.

In the accompanying drawing, Figure 1 is a top view of a form of carbureter embodying my invention; Fig. 2 is a side elevation of the carbureter; Fig. 3 is a central vertical section of the carbureter perpendicular to the axis of the cam shaft; Fig. 4 is an end elevation of the bushing, through which the gasolene supply valve works; Fig. 5 is a cross section on the line 5—5 in Fig. 3; Fig. 6 is a perspective view of the cam controlling the fuel valve; and Fig. 7 is a perspective view of the cam controlling the air valve.

The body or bowl 8 of the carbureter has passing vertically through it the cylindrical air chamber 9, open to the air at its lower end. In the bowl 8 is located the float 10 controlling the gasolene supply valve 11 which is guided by the bushing 11^a, the latter having a cylindrical slotted opening as shown, the slot forming a passage for the flow of fuel into the bowl. In the center of the air inlet chamber 9 is located the gasolene vaporizing nozzle 12, opening upwardly and connecting through the side wall of the chamber 9 with the interior of the bowl 8. Above the chamber 9 and forming an extension thereof, is a larger chamber 13, closed at its top by a plate 14 and having an opening 15 in its side connecting with the cylinder or cylinders of the engine. The fuel valve 16 is a needle valve whose point enters the opening in the

top of the nozzle 12. The shank of this valve is guided in the cap plate 14, and is provided above such cap plate with a head 17 held upwardly against the operating cam about to be described by a spiral spring 18. Supported in standards rising from the cap plate 14 is the cam shaft 19, carrying on its end an operating crank 20, connected by a rod 21 with any suitable means for turning the cam shaft. Upon the cam shaft 19 is secured a cam 22 which bears upon the head of the fuel valve 16, depressing the same against the force of the spring 18 and controlling the opening in the nozzle 12. The cam 22 is secured to the shaft 19 by means whereby it may be adjusted rotatively upon such shaft for a purpose to be presently explained; such means is illustrated as a set screw 23 (Figs. 1 and 2). Resting at its lowermost or closed position upon the platform forming the bottom of the chamber 13 is the air valve 24. This air valve is an annular plate from the center opening in which depends a cylindrical skirt 25, extending centrally down into the air chamber 9 and surrounding the outlet of the nozzle 12 when the air valve is at its lowermost or closed position (Fig. 3).

Extending upwardly from the air valve are two rods 26, 27, passing through and guided in the cap plate 14, and connected at their upper ends above the cam shaft 19 by a cross bar 28. Springs 29, 30 surround the rods 26, 27 beneath the cap plate 14 and act to close the air valve. Upon the cam shaft 19 is secured a cam 31 which may be adjustable on said shaft, or is preferably fixed thereon by means of a cross pin. This cam bears against the under side of the cross bar 28, and when the cam shaft is rotated so as to bring the cam 31 into action, this cam forces the cross bar upwardly against the tension of the springs 29, 30, lifting the air valve 24 from its seat. The cams 22 and 31 are constructed as shown so that they can be nested together upon the cam shaft 19, and, while being independent and relatively adjustable, will both bear centrally with respect to the general axis of the apparatus upon their co-operating parts.

In the operation of the carbureter, when the engine is started, the air valve 24 will be closed and the fuel valve 16 will be opened to the desired extent by means of a cam 22, which is moved by the shaft 19 by the agency

of the rod 21. The air passage will then be restricted to the area provided by the small cylinder 25, which, surrounding the nozzle 12, produces a rapid flow of air around the nozzle, notwithstanding the slow movement of the engine, and effectively vaporizes the gasoline. When the engine has acquired its normal speed, a further movement of the cam shaft 19 will bring the cam 31 into action, lifting the air valve 24 from its seat and enlarging the air passage to the desired extent up to the full capacity of the air chamber 9. The nozzle 12 being located in the center of the air column a thorough mixture of the fuel with the air is secured under all conditions. By adjusting rotatively the relative positions of the cams 22, 31, upon the shaft 19, as by adjusting the cam 22 thereon, the extent of opening of the fuel valve can be regulated with respect to the extent of opening of the air valve, so as to produce a proper mixture of the vapor and air to give the best effect with different kinds or grades of the liquid fuel.

25 What I claim is:

1. In a carbureter, the combination with a cylindrical air chamber and a fuel nozzle located axially therein, of an annular air valve provided with a skirt from its central opening surrounding the fuel nozzle when the air valve is closed, a central needle valve controlling the opening in the nozzle, and rotating cams for operating the air valve and the fuel valve, simultaneously, substantially as set forth.

2. In a carbureter, the combination with a cylindrical air chamber and a fuel nozzle located axially therein, of an annular air valve provided with a skirt from its central opening surrounding the fuel nozzle when the air valve is closed, a central needle valve controlling the opening in the nozzle rotating cams for moving both valves and means for

adjusting the relative movement of the air and fuel valves, substantially as set forth. 45

3. In a carbureter, the combination with a cylindrical air chamber and a fuel nozzle located axially therein, of an annular air valve having a cylindrical skirt surrounding the fuel nozzle when the air valve is closed, 50 a needle fuel valve passing axially through the air valve, rods extending from the fuel valve and air valve through the top of the carbureter, and cams acting simultaneously upon both sets of rods to move the valves 55 together, substantially as set forth.

4. In a carbureter, the combination with a cylindrical air chamber and a fuel nozzle located axially therein, of an annular air valve having a cylindrical skirt surrounding 60 the fuel nozzle when the air valve is closed, a needle fuel valve passing axially through the air valve, rods extending from the fuel valve and air valve through the top of the carbureter, and relatively adjustable cams 65 acting simultaneously upon both sets of rods to move the valves together, substantially as set forth.

5. In a carbureter, the combination with fuel and air valves, of spring rods moving 70 such valves in one direction, a cam shaft located between parts connected with said valves, and independent relatively adjustable cams carried by said cam shaft and bearing on such valve parts against the 75 spring pressure, such cams being nested or overlapping so as to bear centrally with respect to the axis of the carbureter, substantially as set forth.

This specification signed and witnessed 80 this 25th day of May, 1907.

JOSEPH C. SCHNERLE.
